UNITED STATES PATENT OFFICE.

OWEN W. THOMAS, SPENCER L. THOMAS, AND EMIL E. PETERSON, OF MINNEAPOLIS, MINNESOTA.

OIL BURNER.

Application filed January 14, 1924. Serial No. 685,981.

To all whom it may concern:

Be it known that we, OWEN W. THOMAS, SPENCER L. THOMAS, and EMIL E. PETERSON, citizens of the United States, residing in 5 Minneapolis, in the county of Hennepin and State of Minnesota, have invented a new and useful Oil Burner, of which the following is a specification.

Our invention relates to improvements in 10 oil burners.

Its object is to provide a simple and durable device of the present nature adapted to operate effectively and economically and designed to be produced and installed at 15 relatively small cost.

A further object is to furnish a burner of limited dimensions, the same providing for the effective vaporization of liquid fuel and for the provision of air at different levels, 20 the air supply at one level supporting combustion at its source and the other augmenting and spreading the flame, whereby the maximum of air may be employed in the gaseous mixture and accumulations of carbon thereby avoided.

With the foregoing and other objects in view, which will appear in the following description, the invention resides in the novel combination and arrangement of parts and 30 in the details of construction hereinafter described and claimed.

In the drawings, Fig. 1 is a vertical, central, sectional view of an oil burner embodying our invention; Fig. 2 is a plan view 35 thereof; Fig. 3 is a detail sectional view, the same being taken on the line 3—3 of Fig. 1; Fig. 4 is a sectional view taken on the line 4—4 of Fig. 1 and Fig. 5 is a similar view taken on the line 5—5 of Fig. 1.

The present burner is of the gravity type, the combustion supporting air being introduced at atmospheric pressure and the liquid fuel fed by gravity. The device includes a base A having a neck 10 formed axially thereof, said base being hollow and providing for the ingress of air upwardly into and through said neck. A hollow vaporizing head B is supported with the bottom thereof spaced slightly above the rim of the neck 10 to form an annular orifice 11 between said head and neck. This structure is ordinarily placed at the center of a stove or furnace grate 12 (see Fig. 1), that portion of the grate not covered by the burner structure 50 being closed with sheet metal as at 13 to

confine a bed of sand 14 within the fire box of the heater and about the base of our burner.

The annular shell-like body 15 of the base A is open at the bottom thereof and permits 60 of the passage of air upwardly through a supporting grate and into and through the neck 10. Said neck is of relatively large diameter and is preferably cast integrally with the top 16 of the base A, spaced vertical ribs 17 inside of the neck 10 have depending portions extending well beneath the top 16 of the base A. Cast integrally with said depending portions of said ribs is a catch basin 18, the purpose of which will 70 more fully hereinafter appear. Rising centrally from the basin 18 is a stem 19 having a longitudinal bore 20 therein and an external flange 21 thereon slightly above the mouth of the neck 10.

The head B has the form of an inverted frustum, the same being hollow and including a core 22, a top 23, an outwardly and upwardly flaring annular side wall 24 and a bottom piece 25. Said bottom piece 25 may 80 be cast integrally with the core 22, but we find that the molding of the head B is simplified by constructing said bottom piece 25 apart from the head proper. The core 22 and bottom piece 25 have axial bores thread- 85 ed internally to fit the upper threaded end of the stem 19 and to permit of the seating of said bottom piece 25 against the flange 21.

An annular marginal opening 26 provided in the bottom of the head B issues downwardly into the restricted annular orifice 11 formed between the lower margin of said head B and the rim of the neck 10. Within 90 the head B and spaced slightly beneath the top 23 thereof is a spreader plate 27. This plate is cast integrally with the core 22 and is joined with said top 23 by means of spaced bosses 28. Inside of the wall 24 are upwardly inclined step-like ledges 29 forming a series of annular troughs. The inner 95 edge of the upper ledge 29 reaches inside of the outer edge of the spreader plate 27 and the inner edge of each of the remaining ledges reaches inside of the inner edge of the ledge 29 thereabove. A liquid fuel supply 100 pipe 30, fitted with a control valve (not shown), feeds into the bore 20 of the stem 19 at the lower end thereof. Rising through this bore, liquid fuel flows outward over the spreader plate 27, thence drips into the 105

110

trough formed by the uppermost ledge 29. The overflow from this trough drips into the trough formed by the second ledge 29 and if there is any overflow from said second trough, due to the incomplete vaporization, the drip is caught in the third trough formed by the lowermost ledge 29. Vapor formed within the head B issues from the annular opening 26 and meeting the upward moving air at the mouth of the neck 10 mixes with said air and passes outward through the annular orifice 11. Issuing from this narrow orifice, the mixture is readily combustible, the flame, upon ignition, burning beneath and on all sides of the head B and thereby heating and constantly vaporizing the incoming fuel. The orifice 11 is necessarily restricted and to augment the supply of air, we form an annular slot 31 in the neck 10 just beneath the rim thereof. The ribs 17 are not severed by this slot and therefore support the ring-like upper end of said neck.

An upright flange 32 at the margin of the top 23 of the head B forms a receptacle 33 for a generating medium and an annular depression 34 in the top 16 of the base A forms a similar receptacle.

In use, the burner is pre-heated by placing oil or the like in the receptacles 33 and 34, a bit of waste or other wicking being placed in the oil to promote combustion, particularly, when the oil is of crude nature. Having heated the head B with the generating fluid, oil is admitted to said head B through the pipe 30, the same being vaporized in its passage through the head. The vapor issuing from the opening 26 and mixing with air from the neck 10 during its passage outward through the orifice 11, burns readily in an annular outwardly flaring flame. Supplied with an abundance of air from the slot 31, beneath the orifice 11 combustion is augmented and an intense, clean burning flame is produced, the same being flattened by the effect of said augmenting air and thereby induced to occupy a zone reaching approximately horizontally toward the sides of the heater.

The basin 18 is a safety feature and serves, when the flame from the burner is accidentally extinguished, to catch the unvaporized liquid flowing through the head B. In this connection attention is invited to the fact that the vapor outlet 26 in the head B is confined within the diametrical limits of the neck 10, while the rim of the neck 10 and the bottom 31^a of the slot 31 slope inwardly. Thus constructed, any drip from the outlet 26 finds its way through the neck 10 to the basin 18. A pipe 35 serving to drain the basin 18 leads to a conventional valve closing device (not shown) for cutting off the supply of liquid fuel.

An opening in the top 23 of the head B

is fitted with a threaded plug 36 and permits of access to the interior of the head for cleaning purposes should that be necessary.

Changes in the specific form of our invention, as herein disclosed, may be made within the scope of what is claimed without departing from the spirit of our invention.

Having described our invention, what we claim as new and desire to protect by Letters Patent is:

1. In a device of the class described, a base formed with a neck thereon and providing for the ingress of air into and through the neck, said neck having an annular air outlet slightly beneath the rim thereof, a catch basin within the body of the base and beneath said neck, a hollow stem rising from said catch basin centrally through said neck, a hollow vaporizing head formed like an inverted frustum of a cone and centrally supported on said stem with the bottom of said head spaced slightly above the rim of the neck to form a restricted gas orifice, said bottom of said head being formed with a marginal vapor outlet issuing downward into said orifice and confined within the diametrical limits of said neck, means for feeding liquid fuel into the stem at the lower end thereof, the upper end of said stem opening into the upper portion of the head, a spreader plate within the head for distributing liquid radially from said stem, ledges within the head forming annular step-like troughs, said plate being arranged to feed liquid to the upper trough, each of the remaining troughs being adapted to feed to the trough therebeneath and a drain pipe leading from said catch basin.

2. In a device of the class described, a base formed with a neck thereon and providing for the ingress of air into and through said neck, a hollow annular vaporizing head having a marginal outlet in the bottom thereof, a hollow central mounting rising from the base and supporting said head slightly above the neck to form an annular orifice between the lower side of said head and the rim of the neck, said neck having an annular air outlet beneath said orifice, said mounting providing a liquid fuel duct leading into the upper portion of said head, a spreader plate within the head for distributing the liquid fuel radially from said duct and step-like annular ledges formed internally of the head, the uppermost ledge being adapted to catch the liquid fuel dripping from said spreader plate and each of the remaining ledges being adapted to catch such fuel from the ledge immediately thereabove.

3. In a device of the class described, a base formed with a neck thereon and providing for the ingress of air upwardly through said neck, a hollow vaporizing head

formed like an inverted frustum of a cone and supported with the bottom thereof slightly above said neck to provide an annular gas orifice, the bottom of said head 5 having a marginal vapor outlet issuing downwardly into said orifice, means for feeding liquid fuel into the head at the top thereof, concentric ledges within the head forming annular step-like troughs and a 10 spreader member over-reaching said ledges, said member being adapted to distribute the fuel and feed it into the uppermost trough, said troughs serving to retard the descent of the fuel in the head.

15 4. In a device of the class described, a base formed with a neck thereon and providing for the passage of air upwardly therethrough, a hollow vaporizing head above the base, means for feeding liquid 20 fuel into the head, said head and base forming between them an annular gas orifice, said head having an annular vapor outlet therein, said outlet and said neck respective-

ly providing for the feeding of fuel vapor and air into said orifice and an annular 25 opening in the neck beneath said orifice for feeding air to the products issuing from the orifice.

5. In a device of the class described, a base formed with an air passageway extending upwardly therethrough, a hollow vaporizing head formed with an annular vapor outlet therein and supported above the base, means for introducing liquid fuel into the head, said head and base forming between 30 35 them a restricted annular gas orifice, said vapor outlet and said air passageway feeding into said orifice, said base being formed with an auxiliary opening adjacent the orifice for feeding air to the products issuing 40 therefrom.

In testimony whereof, we have signed our names to this specification.

OWEN W. THOMAS.
